Robert S. Phillips
ATTORNEY

UNITED STATES PATENT OFFICE.

ERNEST LEONARD FORD, OF DARLINGTON, ENGLAND.

EXHAUST VENTILATOR.

Original application filed October 25, 1924, Serial No. 745,915. Divided and this application filed May 9, 1925. Serial No. 29,341.

To all whom it may concern:

Be it known that I, ERNEST LEONARD FORD, a subject of the King of Great Britain and Ireland, residing at Honeypot Works, 5 Honeypot Lane, Darlington, in the county of Durham, England, have invented certain new and useful Improvements in Exhaust Ventilators, of which the following is a specification.

10 This invention relates to automatic exhaust ventilators for the closed compartments or bodies of vehicles, and it has for its object a construction which is highly efficient at all speeds at which the vehicle may be 15 moving, which has no moving or loose parts liable to get out of order or lost, and which has a presentable appearance.

This case is a division of the copending case Serial Number 745,915, filed October 25, 20 1924, and which has matured into Patent, Number 1,568,373, dated January 5, 1926.

I attain these ends by the construction shown in the accompanying drawing in which Figures 1, 2 and 3 are views in side elevation, end elevation and plan, and Figure 4 is a view in longitudinal section on line *w w* Figure 3.

Throughout the views similar parts are marked with like numerals of reference.

30 The hollow body 1 which forms the exhaust chamber is of lozenge or rhomb shape and has both its sides 2 and its top 3 of convex form. In each of the sides 2 are two apertures 4 and 5 the apertures 4 being 35 approximate to one end of the body and those 5 being approximate to the other end thereof. These apertures are of approximately V-shape with their apices towards the ends of the body. On each side of the 40 body are two exterior plates forming deflectors 6 and 7 which are preferably inclined or curved so as to coincide or register with the edges of the apertures nearest to the ends of the body. At the tops of the 45 deflectors 6 and 7 are horizontally or approximately horizontally disposed plates 15 which extend towards the centre of the body and preferably taper towards said point. These plates 15 may be provided with apertures 16 which operate to intensify the negative pressure at the apertures 4 or 5 by 50 reasons of the flow of air over said openings.

The central part of the base is formed by

two inclined plates 11 which slope upwardly towards one another and form by and between them a relatively narrow centrally arranged transverse aperture 12. The edges of the aperture 12 are preferably shaped to form upwardly curved lips 13. On each of the plates 11 is a series of vertically arranged plates 17 which extend between the base and the top or roof 3. These plates 17 are angularly arranged so that their ends nearest to the ends of the body are inclined towards the longitudinal centre of said body 60 and they are so located relative to each pair of apertures 4, 4 and 5, 5 that they partly register with said apertures.

The action of the ventilator is as follows:— Directly the vehicle is in motion and so long 70 as it continues to move at a slow speed a current of air strikes the front pair of deflectors—say 6 and 6—and is deflected by them over the front pair of apertures 4 and 4 thus setting up a negative pressure or 75 partial vacuum at said apertures. This negative pressure creates a similar negative pressure in the interior of the body 1 which causes a suction action at the central aperture 12 in its base thereby extracting the 80 air out of the body of the vehicle 12 through the hole in the roof with which said aperture registers. The current of air after passing the front pair of deflectors 6 and 6 flows inwards again towards the sides 2 and 85 3 is caught by the rear pair of deflectors 7 and 7 and is deflected into the interior of the chamber through the rear apertures 5 and 5 at an increased positive pressure which flowing over the aperture 12 augments the 90 negative pressure in the front part of the chamber and assists to increase the suction effect at the central aperture 12. This suction effect is maintained even at extremely 95 low speeds by reason of the restricted area of the chamber at its central aperture by reason of the upward slope of the inclined plates 11, the upturned lips 13 of the inclined plates 11 at the edges of the central aperture and the arrangement of the plates 100 17. When higher speeds are attained the area of negative pressure set up by the front pair of deflectors is considerably increased and extends completely around the outside of the body so that a negative pressure is 105 also set up at the rear apertures as well as

at the front ones whereby a negative pressure or partial vacuum is produced at both ends of the interior of the body. When a side or three-quarter wind is blowing, the 5 exterior deflectors facing the wind coact with the interior deflector plates to set up the necessary ejector action.

What I claim is:—

1. An exhaust ventilator comprising a 10 chamber which consists of a base having a transversely arranged opening at the centre of its length, a top and a pair of converging side walls having openings located in opposed pairs near the ends of the chamber; 15 plates forming exterior deflectors on the side walls of said chamber adjacent to said side openings; and a plurality of vertically arranged deflector plates located within said chamber on each side of the transverse aperture in the base.

2. An exhaust ventilator comprising a 20 chamber consisting of a base having a centrally located transverse opening, a top, and sides connecting said top and said base which 25 converge towards each other and in which are angularly-shaped apertures which are located in opposed pairs near the ends of the chamber; inclined plates on the side walls of said body forming exterior deflectors 30 which register with the upper edges of said angularly-shaped apertures; and a plurality of vertically arranged deflector plates in interior of the chamber on either side of the transverse aperture in the base.

3. In combination in an exhaust ventilator 35 a lozenge chamber comprising a base which slopes upwardly towards the centre and has a centrally located transverse opening, a top, and side walls extending between said base 40 and said top and having angularly-shaped apertures which are located in opposed pairs near the ends of the chamber; inclined plates forming exterior deflectors on the side walls of said chamber which register with the 45 edges of said apertures nearest to the ends of the chamber; and a plurality of angularly arranged vertical plates located in proximity to the two edges of the central aperture in the base of the chamber which operate as interior deflectors.

4. In combination in an exhaust ventilator, 50 a lozenge chamber comprising a base which slopes upwards towards the centre of its length and has a transverse opening at such mid position, a top, and side walls which converge towards the ends of the apparatus and have angularly-shaped apertures which are located in opposed pairs near the ends of said chamber each with its apex towards 55 the adjacent end of the apparatus; inclined plates forming exterior deflectors on the side walls of said chamber which register with the edges of said apertures nearest to the

ends of the apparatus; horizontally disposed apertured extensions of the exterior deflectors, and a plurality of angularly arranged vertical plates located in proximity to the two edges of the aperture in the base of the chamber.

5. A double-ended symmetrical exhaust 70 ventilator comprising a base sloping upwards towards the centre of its length and having a transversely arranged opening at its centre, a top above said base, a pair of forwardly converging side walls and a pair 75 of rearward converging side walls between said base and said top and having an opening in each of said side walls, a pair of forwardly and a pair of rearwardly inclined plates on the exterior of the side walls adjacent of said openings in said side walls, and a plurality of vertical angularly arranged plates extending between the base and the top on each side of the transverse opening in said base.

6. A double-ended symmetrical exhaust 80 ventilator comprising a base sloping upwards towards the centre of its length and having a relatively narrow transversely arranged opening at said centre, a top above 85 said base, a pair of forwardly converging side walls and a pair of rearward converging side walls between said base and said top and having angular openings the edges of which nearest to the ends of the ventilator 90 slope upwards and backwards from the base to the top, a pair of forwardly and a pair of rearwardly inclined plates on the exterior of the side walls which register with the 95 sloping edges of the openings in said side walls, and a plurality of deflector plates in the interior of the ventilator on each side of the central opening in the base and extending vertically from the base to the top.

7. A double-ended symmetrical exhaust 100 ventilator comprising a base which slopes upwards towards the centre of its length and has a relatively narrow transversely arranged opening at said centre, a top above 105 said base, a pair of forwardly converging side walls and a pair of rearward converging side walls between said base and said top and having angular openings the edges of which nearest to the ends of the ventilator 110 slope upwards and backwards from the base to the top, a pair of forwardly and a pair of rearwardly inclined plates on the exterior of the side walls which register with the 115 sloping edges of the openings in said side walls, horizontally disposed apertured extensions of said inclined plates at their upper ends, and a plurality of angularly arranged vertical plates extending from the base to the top and located on each side of the transverse opening in the base.

ERNEST LEONARD FORD.
